CLAIM

The ornamental design for an inflow water treatment fitting for chemical toilet, as shown and described.

DESCRIPTION

FIG. 1 is a front perspective view of an inflow water treatment fitting for chemical toilet, showing my new design;

FIG. 2 is an elevational view of the front side thereof;

FIG. 3 is an elevational view of the rear side thereof;

FIG. 4 is a top plan view thereof;

FIG. 5 is a bottom plan view thereof; and,

FIG. 6 is an elevational view of one end thereof, the other end being a mirror image of the figure shown.
